UNITED STATES PATENT OFFICE.

JAMES H. JOHNSON, OF KANSAS CITY, MISSOURI, ASSIGNOR OF FORTY-NINE PER CENT
TO ALEXANDER L. SMITH, OF KANSAS CITY, MISSOURI.

PORTABLE KITCHENETTE.

1,407,158.

Specification of Letters Patent. Patented Feb. 21, 1922.

Application filed October 12, 1920. Serial No. 416,425.

To all whom it may concern:

Be it known that I, JAMES H. JOHNSON, a citizen of the United States, residing at Kansas City, in the county of Jackson and 5 State of Missouri, have invented certain new and useful Improvements in Portable Kitchenettes, of which the following is a specification.

My invention relates to portable kitchenettes and one object is to provide a convenient and sanitary device of this character in which a variety of canned and other foods, cooking utensils, knives, forks, dishes, etc., can be safely carried.

15 Another object is to provide a device which can be readily applied to a motor vehicle for use by tourists and others, and one in which the door or closure is arranged to open up and serve as a table.

20 Other objects will hereinafter appear and in order that the invention may be fully understood, reference will now be had to the accompanying drawings, in which:

Fig. 1 is a fragmentary rear elevation of 25 an automobile equipped with the invention.

Fig. 2 is a side elevation.

Fig. 3 is a perspective view of the kitchenette with the lid in open position to serve as a table.

30 Fig. 4 is a detail perspective view of a frame which aids in supporting the kitchenette in position on an automobile.

Referring now in detail to the various parts, 2 designates the kitchenette which 35 consists of a rectangular cabinet or receptacle, the back 4 of which is of proper shape to fit the curvature of the back A of the automobile and provided with a pad or cushion 6 to prevent it from marring the finish

40 on the back of the automobile. The front of the kitchenette 2 slopes downwardly and outwardly from top to bottom as disclosed on Fig. 2, to add to its appearance and also to increase the capacity of its lower portion.

45 The front portion of the receptacle 2 is provided with a lid or door 8 adapted to be let down to the position disclosed on Fig. 3, to serve as a table. Strips of rubber or other suitable material 9 are secured to the mar-

50 gins of the receptacle 2 and the door 8, to exclude dust and other foreign matter when said door is in closed position. Said door 8 is connected at its lower portion by hinges 10 to a strip 12 rigidly secured to the lower

55 front portion of the receptacle.

The door 8 is reinforced with cleats 14 and when in lowered position is supported by a leg 16 connected at its upper end by a hinge 18 to the door 8. The lower portion of the leg 16 has a slot 20 to allow it to pass 60 over a staple 22 where it is secured from swinging outwardly by a pin 24. The door 8 is secured in closed position by a hasp 26 secured to the top wall 28 of the receptacle and adapted to pass downwardly over a 65 staple 30, which like the staple 22 is secured to the door 8. If desired a padlock 32 may be used to lock the hasp 26 to the staple 30 in the usual manner.

The interior of the receptacle is divided 70 into compartments by shelves 36, 38 and 40 and vertical partitions 42, 44, 46 and 48. In some instances the shelves may be grooved as indicated at 50, so that the partitions may be adjusted closer together or farther 75 apart as desired.

52 designates a frame made, preferably, of angle iron and in which the bottom of the receptacle 2 rests. Said frame is firmly secured to the bottom of the car body by 80 bolts 54. The frame 52 is aided in supporting the receptacle 2 in position on the back of the car by metal straps 56 and leather straps 58. Each metal strap 56 consists of sections connected by pivots 60 and 85 the lower section is connected by a pivot 62 to a lug 64, which is riveted or otherwise secured to the frame 52. The uppermost sections of the metallic straps 56 are formed into hooks 66 to engage over the hangers B 90 of the automobile, where they are reliably secured by bolts 68 as disclosed on Figs. 1 and 2.

The leather straps 58 are provided with buckles 70, so that they may be let out or 95 taken up as required and extend over the hanger arms C and through rings 72 carried by links 74 swiveled on the ends of a tie-rod 76 arranged in front of the shelf 40 and passing through side walls 42 of the receptacle 2. The ends of the tie-rods 76 are threaded and provided with nuts 78 to hold the links 74 upon said tie-rod and prevent the side walls of the kitchenette from spreading apart.

When the kitchenette is carried at the back of the automobile, I provide it with a bracket 80 upon which the tail light (not shown) of the automobile may be mounted.

In practice the kitchenette may be made 110

of wood, sheet metal, or other suitable material, or a combination of materials, and if preferred may be designed to be carried on the running board of the automobile, in which case the frame 52 and the metallic straps 56 may be dispensed with.

From the foregoing description it will be understood that I have provided a kitchenette which can be readily applied to or re-
10 moved from an automobile and when in use provides tourists and picnickers with all of the conveniences above pointed out, and while I have shown and described the preferred form of the invention I reserve the
15 right to make such changes in the construction, combination and arrangement of parts as properly fall within the spirit and scope of the claims.

Having thus described my invention, what
20 I claim and desire to secure by Letters Patent, is:

1. In combination, a receptacle having a curved back designed to snugly fit the curved back of a motor vehicle, cushioning means on said back to protect the finish on
25 the back of said motor vehicle, shelves and partitions dividing said receptacle into compartments, a closure to said receptacle adapted to serve as a table when adjusted to open
30 position, a support for the free end of said closure when the same is opened, and means for securing the receptacle to a motor vehicle.

2. In combination, a receptacle, a closure

to said receptacle adapted to serve as a table 35 when adjusted to open position, a support to coact with the receptacle in supporting said closure when the same is opened and fold against said closure when the same is closed, a frame adapted to be secured to a 40 motor vehicle and support the receptacle, and metallic straps operably connected at their lower ends to said frame and formed into hooks at their upper ends for engagement with parts of the motor vehicle to aid 45 in supporting the receptacle, and bolts extending through the open ends of said hooks to hold them in engagement with said parts of the motor vehicle.

3. In combination, a receptacle, a closure 50 to said receptacle adapted to serve as a table when adjusted to open position, a support to coact with the receptacle in supporting said closure when the same is opened and fold against said closure when the same is 55 closed, a frame adapted to be secured to a motor vehicle and support the receptacle, a tie rod extending through said receptacle, rings associated with the ends of said tie rods, and straps connected to said rings and 60 adapted to be connected to the motor vehicle to aid in supporting the receptacle.

In testimony whereof I affix my signature, in the presence of two witnesses.

JAMES H. JOHNSON.
